W. A. PECK

TOOL HOLDER

Filed June 14, 1923

Inventor
William A. Peck

By Watson E. Coleman
Attorney

UNITED STATES PATENT OFFICE.

WILLIAM A. PECK, OF NEW HAVEN, CONNECTICUT.

TOOL HOLDER.

Application filed June 14, 1923. Serial No. 645,315.

To all whom it may concern:

Be it known that I, WILLIAM A. PECK, a citizen of the United States, residing at New Haven, in the county of New Haven and State of Connecticut, have invented certain new and useful Improvements in Tool Holders, of which the following is a specification, reference being had to the accompanying drawings.

10 This invention relates to tool holders and more particularly to an extension shank for a wood bit or auger.

An important object of the invention is to provide in a device of this character a 15 socket for the reception of the squared portion of the shank of the auger, in combination with a segmental sleeve which by its engagement in the socket forces the squared portion of the shank of the tool into a portion 20 of the socket formed to receive the same and at the same time grasps a round portion of the shank to steady the same.

A further object of the invention is to provide in a structure of this character a construction whereby the segments of the sleeve 25 are enabled to operate as retaining and clamping jaws.

A still further object of the same is to provide a device of this character which provides a three-point retaining engagement 30 between the socket and the shank.

These and other objects I attain by the construction shown in the accompanying drawings, wherein for the purpose of illustration is shown a preferred embodiment of 35 my invention and wherein:—

Figure 1 is a side elevation of a tool constructed in accordance with my invention;

Figure 2 is a vertical sectional view showing the tool before the locking sleeve is 40 fully inserted;

Figure 3 is a similar view showing the locking sleeve fully inserted;

Figure 4 is a section on the line 4—4 of 45 Figure 3 and

Figure 5 is a section on the line 5—5 of Figure 2.

Referring now more particularly to the drawings, the numeral 10 indicates a tool holder having a socket 11 formed to fit the squared tapered head 12 of an auger or similar boring instrument 13. The tool holder is provided at that end thereof having formed therein the socket 11 with a tubular extension 14, the interior surface of 50 which adjacent the outer end is provided

with screw threads 15. Between the screw threads and the inner end of the tubular extension, the wall of the extension is relieved, as at 16, to a depth such that its internal diameter is greater than the diameter of the tubular extension at the base of the threads 15.

In combination with a tool holder of this character I provide a sleeve 17 which is 60 formed of a plurality of sections 18 which may be assembled about the shank 19 of the bit. As is well-known to those familiar with the art, the shanks 19 of these bits are of less size than the squared heads 12 65 thereof and are connected with these squared heads by a conical portion 20. The inner end of the sleeve 17 is provided with external screw threads 21 coacting with the internal screw threads 15 of the tubular extension 14. The outer end of the sleeve is provided with a knurled portion 22 for engagement by the hand so that the sleeve 70 may be rotated. Adjacent faces of the outer ends of the sections 18 are relieved. 75 In the present instance this relief is accomplished by forming in these adjacent faces interlocking teeth 23, the depth of the teeth increasing toward the outer end of the sections. The outer surface of the sleeve at 80 the threaded inner end thereof is relieved as indicated at 24, the degree of relief increasing toward the inner end of the sleeve. The inner end face of the sleeve is tapered, as at 25, for coaction with the conical portion 90 90 connecting the head and shank of the bit.

In practice the threads on the sleeve sections 18 initially loosely engage in the threads 15 of the tubular extension. The 95 drill is first inserted and seated in the socket 11. The sleeve is then assembled about the shank of the drill and the end thereof engaged about the screw threads and the sleeve rotated until the inner end thereof has forced 100 the head 12 of the bit into firm engagement with the socket 11. Continued rotation of the sleeve will cause the sections 18 thereof to spread at their inner ends, forcing the threads 21 into firm engagement with the 105 threads 15 of the tubular extension so that these threads provide a fulcrum upon which the sections swing under the wedging action applied to the inner ends thereof. This swinging of the sections forces the outer ends 110 of the sections into firm engagement with the shank of the tool, with the result that the bit

is very firmly held, the head end thereof being firmly seated in the socket and being held against withdrawal from the socket by the inner end of the sleeve and the shank of the drill being engaged and centered by the outer ends of the sections. In order to permit of the insertion of drills the heads of which are larger than the internal diameter of the threaded portion of the socket of the holder, I form in the threads 15 of the tubular extension 14 notches 26 aligning with and forming continuations of the corners of the squared socket 11, thus permitting the use of a bit the head of which is greater in 15 diagonal cross section than the internal diameter of the threads 15.

From the foregoing it will be obvious that the strain placed upon the bit is resisted at three points and accordingly the bit will 20 be very firmly held. It will furthermore be obvious that the structure hereinbefore set forth is capable of some change and modification without in any manner departing from the spirit of my invention and I accordingly do not limit myself to such specific structure except as hereinafter claimed.

I claim:

1. A tool holder for tools having angular heads connected with the shanks thereof by 30 conical portions, comprising a body formed with a socket to receive and fit the head of the tool and with a tubular extension beyond the socket having its outer end portion internally screw-threaded and its interior relieved inwardly of the screw threads to a diameter greater than the interior diameter of the sleeve at the base of the screw threads, and a segmental sleeve externally screw-threaded to loosely engage the screw threads 35 of said extension, the inner ends of the segments of the sleeve engaging said conical portion of an engaged tool to be spread thereby whereby the threads of the sleeve are firmly engaged with the threads of the tubular extension and the outer ends of the segments of the sleeve clamped upon the shank of the engaged tool.

2. A tool holder for tools having angular heads connected with the shanks thereof by 50 conical portions, comprising a body formed with a socket to receive and fit the head of the tool and with a tubular extension beyond the socket having its outer end portion internally screw-threaded and its interior relieved inwardly of the screw threads to a diameter greater than the interior diameter of the sleeve at the base of the screw threads, and a segmental sleeve externally screw-threaded to loosely engage the screw threads 55 of said extension, the inner ends of the segments of the sleeve engaging said conical portion of an engaged tool to be spread thereby whereby the threads of the sleeve are firmly engaged with the threads of the tubular extension and the outer ends of the seg-

ments of the sleeve clamped upon the shank of the engaged tool, the outer ends of the segments being relieved to permit their contraction upon the shank of the tool.

3. A tool holder for tools having angular heads connected with the shanks thereof by conical portions, comprising a body formed with a socket to receive and fit the head of the tool and with a tubular extension beyond the socket having its outer end portion internally screw-threaded and its interior relieved inwardly of the screw threads to a diameter greater than the interior diameter of the sleeve at the base of the screw threads, and a segmental sleeve externally screw-threaded to loosely engage the screw threads 75 of said extension, the inner ends of the segments of the sleeve engaging said conical portion of an engaged tool to be spread thereby whereby the threads of the sleeve are firmly engaged with the threads of the tubular extension and the outer ends of the segments of the sleeve clamped upon the shank of the engaged tool, the outer ends of the adjacent faces of said sections being provided with coacting interengaging portions 80 permitting contraction of the outer end of the sleeve.

4. A tool holder for tools having angular heads connected with the shanks thereof by 95 conical portions, comprising a body formed with a socket to receive and fit the head of the tool and with a tubular extension beyond the socket having its outer end portion internally screw-threaded and its interior relieved inwardly of the screw threads to a 100 diameter greater than the interior diameter of the sleeve at the base of the screw threads, and a segmental sleeve externally screw-threaded to loosely engage the screw threads 105 of said extension, the inner ends of the segments of the sleeve engaging said conical portion of an engaged tool to be spread thereby, the outer faces of the inner ends of said segments being relieved.

5. A tool holder for tools having angular heads connected with the shanks thereof by 110 conical portions, comprising a body formed with a socket to receive and fit the head of the tool and with a tubular extension beyond 115 the socket having its outer end portion internally screw-threaded and its interior relieved inwardly of the screw threads, and a segmental sleeve externally screw-threaded to loosely engage the screw threads of said 120 extension, the inner ends of the segments of the sleeve engaging said conical portion of an engaged tool to be expanded thereby, the outer ends of the segments being relieved to 125 permit their contraction upon the shank of the tool, the inner end portion of the segmental sleeve being externally reduced to thereby permit greater expansion of said inner ends by the engagement of said inner ends with the conical portion of the tool. 130

6. A tool holder for tools having angular heads connected with the shanks thereof by conical portions, comprising a body formed with a socket to receive and fit the head of the tool and with a tubular extension beyond the socket having its outer end portion internally screw-threaded and its interior relieved inwardly of the screw threads, and a segmental sleeve externally screw-threaded 10 to loosely engage the screw threads of said extension whereby continued rotation of the sleeve will cause the sections to spread at their inner ends by the wedging action of the conical portion of the tool forcing the threads into firm engagement with the threads of the tubular extension.

7. A tool holder for tools having angular heads connected with the shanks thereof by conical portions, comprising a body formed

with a socket to receive and fit the head of the tool and with a tubular extension beyond the socket having its outer end portion internally screw-threaded and its interior relieved inwardly of the screw threads, and a segmental sleeve externally screw-threaded 25 to loosely engage the screw threads of said extension whereby continued rotation of the sleeve will cause the sections to spread at their inner ends by the wedging action of the conical portion of the tool forcing the 30 threads into firm engagement with the threads of the tubular extension, the inner end portion of the segmental sleeve being externally reduced to thereby permit greater expansion of said inner ends.

In testimony whereof I hereunto affix my signature.

WILLIAM A. PECK.
